UNITED STATES PATENT OFFICE

STRICKLAND KNEASS, JR., OF SEWICKLEY, PENNSYLVANIA, ASSIGNOR TO COSTELLO ENGINEERING COMPANY, OF PITTSBURGH, PENNSYLVANIA, A CORPORATION OF PENNSYLVANIA

VALVE

Application filed December 5, 1928. Serial No. 323,947.

The present invention relates broadly to the art of fluid control, and more particularly to an improved valve structure for this purpose especially designed for the handling of raw producer gases and similar fluids, although the utility of the invention is not limited with respect to the particular use to which the valve is placed.

With many of the gases being handled at the present time, and particularly with producer gases, the solid content is such that the valves and lines used for controlling the flow thereof have a deposit formed therein. This deposit is particularly objectionable when it forms in proximity to the valve inasmuch as it interferes with the proper flow with a predetermined valve setting.

It is one of the objects of the present invention to provide a valve structure of such nature that the building up of deposits in proximity to the working parts thereof is minimized.

Another object of the present invention is to provide a valve having an outlet of such nature that the flow therethrough of the medium being handled is expedited, and the release and deposit of foreign matter will be prevented.

In the accompanying drawings I have shown for purposes of illustration only preferred embodiments of the present invention, it being understood that changes in the construction and operation of the parts therein illustrated may be made without departing either from the spirit of the invention or the scope of the appended claims.

In the drawings, Figure 1 is a vertical sectional view through a valve constructed in accordance with the present invention,

Figure 2 is a transverse sectional view on the line II-II of Figure 1, looking in the direction of the arrows,

Figure 3 is a vertical sectional view along the line III-III of Figure 2, looking in the direction of the arrows, and

Figure 4 is a view similar to Figure 1, illustrating a modified embodiment of the invention.

In accordance with the present invention there may be provided a valve casing 2 of

any desired construction having a seat 3 adjacent the inlet thereof and having a special outlet connection 4.

Extending through the casing is a sleeve 5 having secured to its lower end a cleaning device 6, herein illustrated as comprising a pair of diverging arms with their lower ends shaped to provide scraper blades 7 cooperating with the upper surface of the seat 3.

Extending through the sleeve 5 is a stem 8, carrying at its lower end a valve 9 cooperating with the wall of the inlet surrounded by the seat 3 and of such diameter as to effectively cooperate with the inner edges 10 of the cleaning device 6. By reason of this construction it will be apparent that the valve 9 may be moved from its closed position illustrated in full lines in Figure 1 to its open position indicated in dotted lines in this figure without interference from the cleaning device 6.

On the casing 2 is a yoke 11 carrying a bushing 12 internally threaded to cooperate with the upper threaded portion 13 of the stem 8. This stem above the yoke 11 has secured thereto a hand-wheel 14, so that upon rotation of the hand-wheel the valve 9 may be moved either to open or closed position at will.

Mounted above the casing 2 and between the arms of the yoke 11 is a second hand-wheel 15 secured to the upper end of the sleeve 8, and effective for rotating such sleeve.

With the construction described, it will be apparent that rotation of the hand-wheel 15 is effective through the scraper blades 7 of the cleaning device for removing any foreign material which may be accumulated on the seat surrounding the valve 9. With the valve in any predetermined open or partially open position, such for example as that indicated in dotted lines in Figure 1, the rotation of the hand-wheel 15 will not only be effective for cleaning foreign material from the seat 3, but will also be effective for scraping the peripheral edge of the valve itself. In like manner, each movement of the valve from closed to open position, or vice versa,

will bring the peripheral edges of the valve into contact with the edges 10 and thereby serve to clean the valve simultaneously with each operating movement thereof.

5 Cooperating with the casing and positioned intermediate the same and outlet connection 4 is a removable flow plate 16 of such construction as to provide a constricted orifice 17 in axial alinement with the outlet 4, and a hollow chamber 18 surrounding such orifice. The flow plate is of such construction also as to provide a connection 19 adapted to cooperate with a suitable source of fluid under pressure, such, for example, as 10 steam or air.

15 Formed in the casing 2 in such manner as to surround the sleeve 5 and the valve stem 8, is a second fluid pressure chamber 20 provided with a connection 21 to the chamber 18 in the flow plate. In this manner fluid under pressure is permitted to pass from the flow plate through the connection 21 into the chamber 20, and thence, by way of openings 22, into the annular space 23 intermediate the 20 sleeve 5 and the stem 8. The bearing 24 at the lower end of the sleeve 5, while having a fairly tight fit with the stem 8, does not have a fit of such nature as to preclude the passage of fluid therethrough. It will thus 25 be apparent that during the operation of the valve fluid under pressure will continuously flow between the valve stem and sleeve and tend to prevent the accumulation of any foreign matter therebetween.

30 The flow plate 16 is constructed in such manner as to provide a circumferentially extending slot 25 adapted to discharge in the general direction indicated by the arrows A thereby assisting flow from the interior of 35 the valve casing through the outlet connection 4. Secured to the flow plate is a bent tube 26 having its discharge end 27 directly forwardly in the direction of discharge from the valve, and provided with 40 an outlet 28 substantially in line with the axis of flow through the flow plate. Simultaneously with the discharge of fluid under pressure through the opening 25, fluid will be discharged through the outlet 28, thereby 45 insuring a relatively high velocity such as to preclude the deposit of foreign matter within the flow plate or the outlet connection.

50 It will be further noted that the flow plate and outlet connection are of such contour as to provide a flow passage of approximately Venturi shape, thereby insuring a maximum velocity at substantially the point of maximum in the flow plate. This again tends 55 to prevent the settling of any solid matter from the fluid being handled until such time as its velocity shall have decreased and substantially normal pressure conditions again assumed.

60 65 In Figure 4 of the drawings there is illus-

trated a modified embodiment of the invention, in which parts corresponding to the parts already described are designated by the same reference characters having a prime affixed thereto. In this embodiment of the 70 invention the seat 3' and the cooperating valve 9' are of such shape as to provide a tight seating valve, the valve being adapted to engage the seat upon upward movement of the valve stem 8' when rotated by the 75 hand-wheel 14'. In this figure the parts are illustrated in full lines in the positions they occupy with the valve closed, the corresponding positions of the parts with the valve opened being shown in dotted lines. 80

The sleeve 5' is threaded at its lower end to co-operate with a coupling 29, the opposite end of which carries a guiding gland 30. Secured to the sleeve above the coupling 29 is a hub 30' having arms 31 projecting outwardly and downwardly therefrom. Each of these arms has a pivotal connection 32 to the upper end of a link 33. The lower ends of the links 33 in turn have pivotal connections 34 with the upper ends of scraper blades 35 90 adapted normally to occupy the position indicated in full lines.

When the valve is moved to open position by the operation of the hand-wheel 14', the hand-wheel 15', secured to the sleeve 5', may 95 be pushed downwardly from its full line to its dotted line position, thereby moving the hub 30' with its associated parts, including the scrapers 35, into the position indicated in dotted lines. At this time the outer portions 36 of the scrapers engage the valve seat 3' while the portions 37 engage the outer periphery of the valve. In this position the hand-wheel 15' may be rotated so as to scrape the seat and valve simultaneously and remove 100 therefrom any deposit of foreign material.

Upon the conclusion of the scraping operation the hand-wheel 15' may be returned to its full line position to permit subsequent closing of the valve. If for any reason the 105 hand-wheel 15' is not completely restored to its full line position, it will be apparent that upon upward movement of the valve 9' it will engage the lower ends of the scrapers 35 and effect an upward movement of the sleeve 5' 110 and its associated parts simultaneously with the upward movement of the valve.

Certain advantages of the present invention arise from the provision of a valve structure of such nature as to insure a rapid flow 115 therethrough of fluid being controlled in such manner as to minimize the possibility of solid precipitation.

Another advantage of the present invention arises from the provision of a valve with 120 means associated therewith and effective for cleaning the valve and its seat to effect the removal therefrom of any accumulated matter.

125 130 Still other advantages of the invention

arise from the provision of connections for supplying fluid under pressure to certain of the valve parts during the operation thereof in such manner as to facilitate flow and effect a cleaning of the valve parts subjected to such cleaning fluid.

I claim:

1. The combination with a valve casing having a seat, of a valve adapted to cooperate with said seat, and cleaning means normally occupying a position entirely above the plane of said seat for cleaning the seating face of said valve.

2. The combination with a valve casing having a seat, of a valve adapted to cooperate with said seat, and cleaning means normally occupying a position entirely above the plane of said seat for cleaning the seating face of said valve and said seat.

3. The combination with a valve casing having a seat, of a valve adapted to cooperate therewith, operating connections for said valve, cleaning means for said valve, and other operating connections for said cleaning means extending substantially parallel to said first mentioned operating connections.

4. The combination with a valve casing having a seat, of a valve adapted to cooperate therewith, operating connections for said valve, cleaning means for said valve, and operating connections for said cleaning means, said last mentioned operating connections being disposed in concentric relationship to the operating connections for the valve.

5. The combination with a valve casing having a seat, of a valve adapted to cooperate therewith, a valve stem secured to said valve and projecting upwardly therefrom, a sleeve surrounding said stem, cleaning means operatively connected to said sleeve, and means for effecting individual operation at will of said stem or said sleeve.

6. The combination with a valve casing having a seat, of a valve adapted to cooperate therewith, a valve stem secured to said valve and projecting upwardly therefrom, a sleeve surrounding said stem, cleaning means operatively connected to said sleeve, and means for effecting operation at will of either said stem or said sleeve, said means comprising a hand-wheel for each of said parts.

7. The combination with a valve casing having a seat, of a valve adapted to cooperate therewith, and cleaning means for said valve and seat, said cleaning means comprising scrapers having different portions thereof adapted to cooperate respectively with the valve and seat.

8. The combination with a valve casing, of a valve, operating means for said valve, a Venturi shaped outlet connection for said casing, and means for supplying fluid under pressure to said outlet connection in the direction of flow of fluid therethrough from the valve.

9. The combination with a valve casing, of a valve, a stem for operating said valve, a sleeve surrounding said stem, cleaning means carried by said sleeve, and means for supplying fluid under pressure between said stem and sleeve.

10. The combination with a valve and its seat, of cleaning means comprising a scraper arm, and means for operating said scraper arm to simultaneously clean said valve and seat.

11. The combination with a valve casing, of a valve including a valve stem for controlling flow through the casing, cleaning means for said valve, operating connections including a sleeve surrounding said stem for operating said cleaning means, a flow plate cooperating with said casing, a fluid delivery connection between said flow plate and the space between said sleeve and stem, and means for supplying fluid under pressure to said flow plate and said fluid delivery connection.

12. The combination with a valve casing, of a valve including a stem for controlling flow through said casing, cleaning means for said valve, operating connections for said cleaning means including a sleeve surrounding said stem, a flow plate cooperating with said casing, and connections for supplying fluid under pressure to said flow plate and to the space between said stem and said sleeve, said cleaning means comprising a scraper cooperating with the valve and operable independently thereof.

In testimony whereof I have hereunto set my hand.
